US0D1084342S

(12) **United States Design Patent** (10) Patent No.: **US D1,084,342 S**
(45) Date of Patent: ** Jul. 15, 2025

(54) **SPHYGMOMANOMETER**

(71) Applicant: **AOJ Health Technology Co., Ltd.**,
Guangdong (CN)

(72) Inventors: **Hongtao Wang**, Guangdong (CN);
Mingtian Chen, Guangdong (CN);
Yijuan Yuan, Guangdong (CN)

(73) Assignee: **AOJ Health Technology Co., Ltd.**,
Guangdong (CN)

(**) Term: **15 Years**

(21) Appl. No.: **29/834,246**

(22) Filed: **Apr. 11, 2022**

(30) **Foreign Application Priority Data**

Oct. 12, 2021 (CN) 202130668964.4

(51) **LOC (15) Cl.** **24-02**

(52) **U.S. Cl.**

USPC **D24/165**

(58) **Field of Classification Search**

USPC D24/165, 107, 134, 166, 167, 169, 168,

(57) **CLAIM**

The ornamental design for a sphygmomanometer as shown and described.

DESCRIPTION

FIG. 1 is a top view of the sphygmomanometer showing my new design;

FIG. 2 is a bottom view thereof;

FIG. 3 is a left side view thereof;

FIG. 4 is a right side view thereof;

FIG. 5 is a front view thereof;

FIG. 6 is a back view thereof;

FIG. 7 is a perspective view thereof; and,

FIG. 8 is another perspective view thereof.

The broken lines in the figures illustrate the portions of the sphygmomanometer that form no part of the claimed design.

1 Claim, 8 Drawing Sheets
